Peter J. Dunn

ATTORNEY

UNITED STATES PATENT OFFICE

THOMAS E. DUNN, OF NEW YORK, N. Y.

RACK ATTACHMENT FOR POCKET BILLIARD TABLES

Application filed June 20, 1929. Serial No. 372,323.

This invention relates to a rack attachment for a pocket billiard or pool table having chutes or gutters for conveying the balls from all the pockets to a common discharge outlet.

In a companion application filed of even date I have disclosed a form of attachment having a plurality of racks which are movable selectively in whole or in part into position to receive the balls as they are discharged from the table. In said application I have included claims to cover broadly the subject matter common to both applications.

The present invention has for an object to provide an attachment having a plurality of stationary racks and wherein the discharge outlet has an extension chute movable axially about the outlet to convey the discharged balls to one of the several racks selectively.

The attachment is intended for the convenience of the several players, where there is more than one participant in the game, so that each player, or team in the case of partnership playing, can have a separate rack in which all of the balls pocketed by said player or team may be collected and stored.

The invention consists in the novel construction, combination and arrangement of parts hereinafter described and claimed. It is to be understood that modifications may be made within the scope of the claim.

In the accompanying drawing, illustrating an embodiment of the invention;

Figure 1 is a front view of one form of the improved rack attachment;

Fig. 2 is a vertical sectional view thereof through substantially the longitudinal center line, with the outer ends of the racks broken away;

Fig. 3 is a transverse vertical section on the line 3—3 of Fig. 2; and,

Fig. 4 is a horizontal section taken on the line 4—4 of Fig. 2.

The attachment comprises an open ended

box like casing 1 having an opening 2 through its inner wall. The casing is adapted to be fastened to the discharge end of a pocket billiard or pool table of the type having chutes or gutters for conveying the balls from all the pockets to a common discharge outlet, and with its opening 2 in registration with said discharge outlet.

A plurality of ball storage racks 3 are fixedly supported in the casing with their inner ends arranged in the arc of an imaginary circle whose center is substantially on the center line of the opening 2. A curved sleeve 4 extends from the opening 2 into the interior of the casing and is rotatively secured in said opening, as by means of the collars 5. The sleeve is adapted to turn axially about the opening with its free traveling in an arc concentric with the arc in which the inner ends of the racks are positioned. Said sleeve, in effect, constitutes an extension of the conveying chutes of the table and serves to direct the balls from the discharge outlet on to the several racks selectively. The racks slant downwards slightly from their inner towards their outer ends to facilitate rolling of the balls.

The sleeve has a handle 6 that extends through an arcuate slot 7 in the front wall of the casing. Notches 8, numbered for convenience "1", "2", "0", "4", and "5", respectively, are formed in the lower edge of the slot to indicate the positioning of the sleeve required to discharge the balls on the several racks.

The casing has an opening 9 in its bottom through which the balls may be discharged directly into a basket 10 hanging on a hook 11 when for any reason it is not desired to use the racks. Such discharge is effected when the handle of the sleeve is positioned in the notch "0".

What I claim is:

A rack attachment for a pocket billiard table of the type having chutes for conveying

balls from all the pockets to a common discharge outlet at one end of the table, comprising a group of racks adapted for attachment to said end of the table with their inner ends positioned adjacent the discharge outlet and disposed in an arc of a circle in a vertical plane, and a rotatable tubular sleeve supported in registration with the discharge outlet and adapted to convey balls from said outlet to each of the racks successively.

THOMAS E. DUNN.
